IGNITRON CONSTRUCTION

Donald E. Marshall, Allwood, and William J. Knochel, Irvington, N. J., assignors to Westinghouse Electric & Manufacturing Company, East Pittsburgh, Pa., a corporation of Pennsylvania

Application October 9, 1940, Serial No. 360,358

2 Claims. (Cl. 250—27.5)

Our invention relates to discharge devices and more particularly to the type of discharge device known as sealed-off ignitrons.

An object of our invention is to simplify the arrangement and material of the metal casing of a sealed-off ignitron so that the device will occupy a very small space.

Another object of the invention is to modify the anode structure to eliminate breaking of the anodes.

Other objects and advantages of the invention will be apparent from the following description and drawing in which:

Fig. 1 is a view in cross section of a device embodying our invention.

Fig. 2 is a top elevational view of Fig. 1.

Fig. 3 is a cross section on lines III—III of Fig. 1.

Sealed-off ignitrons such as disclosed in Patent 2,140,369, issued December 13, 1938, in the name of D. E. Marshall, have occupied considerable space and the structure has also utilized considerable material.

It is an object of our invention, as mentioned above, to simplify the casing so that the device will occupy a very small space. In simplifying the casing and reducing the dimensions of the electrodes, we have discovered that the effect on the prior art structure is a tendency to crack the carbon anode usually employed in these devices. Our invention also includes modifying the anode structure to eliminate this cracking of the carbon anode.

In Fig. 1 we have disclosed the cylindrical casing 10, preferably of stainless or cold-rolled steel, having an inverted cap-shaped bottom header 11 welded therein. The cap-shaped header, in combination with the adjacent casing, supports the mercury pool 12. A tubulation 13 extends through the bottom portion of the casing and this tubulation is preferably of a non-corrosive metal such as nickel.

This tubulation has a flange 14 with an eyelet 15 welded thereto. The flange 14 is welded to the top of the header 11 after the tubulation 13 has been inserted through the opening 16 in this header. After the assembled tube has been heat-treated and exhausted, the tubulation is closed off at the tip 17. If desired, a solder 18 may enclose this tubulation and be surrounded by a protecting non-corrosive cap 19 such as brass. The casing 10 may be flanged out at the upper portion thereof at 20 for the purpose of support or for suitable attachment to a water-cooling jacket, or to an air-cooling arrangement, as desired.

We preferably weld a cylinder 21 to the upper interior wall of the casing 10. This cylinder 21 is of an iron-nickel-cobalt alloy sold under the trade name of "Kovar." To the other edge of this cylinder is sealed a cylinder of insulating material 22 preferably of borosilicate glass. At the other end of this cylinder is sealed a cap 23 likewise of the iron-nickel-cobalt alloy sold under the trade name of "Kovar."

10 The cap 23 in place of having a closed end has an integral upwardly extending cylindrical stem portion 24. This stem portion 24 is in turn sealed to a cylindrical borosilicate glass portion 25 that in turn is sealed to a perforated cylindrical cap 26, also of the alloy metal sold under the trade name of "Kovar." Through the central perforation of this cap 26 extends a long ignitor standard 27 which may be of steel. This standard at 28 has an enlarged portion that is welded to the bent-in flange 29 of the cap 26. At the lower end of the standard 27 is a tapered tip 30 of a high resistance material, such as boron carbide, dipping into the mercury pool 12. The upper end of the standard has an enlarged portion 31 to which may be connected a flexible connector to a source of electricity for igniting the device.

To the underside of the cap 23 is welded a cylinder 32, preferably of steel, extending downwardly to the location of the anode 33 which is of carbon. In the prior art such a tubular metal connection was screwed to the carbon anode. It will be noted that the heat applied to the sealing operation of the borosilicate glass 25 and the cap 23, as well as the heat applied to the sealing of the glass 22 to the cap 23, has a good conductive path through this cylindrical member 32 to the carbon anode 33 in these devices of the prior art.

40 It will be noted that the diameter of the casing 10 and the diameter of the carbon anode 33 are greatly reduced over the diameter of the casing and anode in Patent 2,140,369. The result of the transfer of heat from a metal cylinder to the anode to which it was directly screw-threaded caused an uneven expansion of the two connected devices and cracks resulted in the anode. In order to prevent this, we utilize an intermediate sleeve 34 which is directly connected by screw threads to the cylindrical member 32 and then in turn is attached to the anode 33 by screw threads. There is a slight space 35 between the bottom portion of the cylindrical member 32 and the top of the anode 33. The conduction of heat is accordingly cut down before it reaches the anode by the boundary between the

cylindrical member 32 and the sleeve 34, as well as the intervening space 35 between the anode and the cylindrical member 32.

The cap member 23 may be made of very thin material and we preferably copper solder a steel member 36 to the top of this cap 23. On this additional member 36 we preferably silver solder a thick ring 37 of copper which is preferably screw-threaded on its inner side 38, and a cylinder member 39 preferably of copper is attached by similar screw threads to this ring 37. This cylinder member 39 preferably rises to a height to protect the small glass cylinder 25 and the thin cap 26 sealed thereto, and also acts as an electrical connection for the anode 33.

The reason for these various solders is that the iron-nickel-cobalt alloy cannot be used with silver, and the copper solder cannot be used with copper. We desire the cap to be made of iron-nickel-cobalt and the ring 31 to be of copper.

It will be noted that we have simplified the structure of the casing so that the diameter of the main casing 10 may be as small as $1\frac{1}{2}$ inches. Even this device with its small diameter can effectively carry current having 1000 amperes peak and 25 amperes average. It will also be noted that in spite of the reduction of the diameter of the casing and the diameter of the anode, we have greatly strengthened the anode structure over that disclosed in the prior art. We have also made the tubulation and its protection of non-corrosive material so that there will be no danger of leakage therethrough by an accumulation of corrosion.

It is apparent, however, that many modifications may be made in the preferred embodiment disclosed, and accordingly we desire only such limitations to be imposed upon our invention as are necessitated by the spirit and scope of the following claims.

We claim:

1. In a discharge device, a plurality of cylindrical members the body portions whereof are substantially of equal diameter and sealed successively to each other one above another thereby providing an elongated cylindrical chamber of substantially the same size throughout the length thereof, an intermediate one of said members comprising insulating material and the others being of metal, a bottom header for the lower end of said chamber sealed with respect to the lowermost one of said members, the uppermost of said members comprising a cap having a re-

duced hollow neck portion projecting upwardly therefrom, a cylinder axially of said chamber depending from said cap within the body of the same entirely through the member next below said cap, an anode immediately below said depending cylinder, said anode and cylinder having adjacent portions of equal diameter and screw threaded, a sleeve having interior threads throughout its length engaging the threads of both the depending cylinder and anode, said sleeve being of relatively thin metal and tending to stop heat conduction between said depending cylinder and anode, an ignition standard depending from above said neck to the proximity of said header and having a tip on the lower end thereof, and a pool cathode in said chamber into which said tip dips.

2. In a discharge device, a plurality of cylindrical members the body portions whereof are substantially of equal diameter and sealed successively to each other one above another thereby providing an elongated cylindrical chamber of substantially the same size throughout the length thereof, an intermediate one of said members comprising insulating material and the others being of metal, a bottom header for the lower end of said chamber sealed with respect to the lowermost one of said members, the uppermost of said members comprising a cap having a reduced hollow neck portion projecting upwardly therefrom, an upper cylindrical insulating member sealed to the upper end of said neck and having a diameter throughout its length substantially that of the said neck, a cylinder axially of said chamber depending from said cap within the body of the same entirely through the member next below said cap, an anode immediately below said depending cylinder, said anode and cylinder having adjacent portions of equal diameter and screw threaded, a sleeve having interior threads throughout its length engaging the threads of both the depending cylinder and anode, said sleeve being of relatively thin metal and tending to stop heat conduction between said depending cylinder and anode, an ignition standard depending from above said upper insulating member to the proximity of said header and having a tip on the lower end thereof, and a pool cathode in said chamber into which said tip dips.

DONALD E. MARSHALL,
WILLIAM J. KNOCHEL.
